Louis Dagger & Co.

UNITED STATES PATENT OFFICE.

GREVILLE E. CLARKE, OF RACINE, WISCONSIN.

NUT-LOCK.

SPECIFICATION forming part of Letters Patent No. 380,188, dated March 27, 1888.

Application filed September 12, 1887. Serial No. 249,453. (No model.)

To all whom it may concern:

Be it known that I, GREVILLE E. CLARKE, a citizen of the United States, and a resident of Racine, in the county of Racine and State 5 of Wisconsin, have invented certain new and useful Improvements in Nut-Locks; and I do hereby declare that the following is a full, clear, and exact description of the invention, which will enable others skilled in the art to to which it appertains to make and use the same, reference being had to the accompanying drawings, which form a part of this specification, and in which—

Figure 1 is a perspective view of my improved nut-lock, showing the same applied to the fish-plate of a rail-joint. Fig. 2 is a perspective view of the washer-plate shown in Fig. 1 and of the spring, the same being detached from each other. Fig. 3 is a plan view 20 showing a different form of the washer and spring—a slight modification. Fig. 4 is a similar view of another slight modification, and Fig. 5 is a vertical sectional view through the bolt with its nut and nut-lock.

25 The same letters of reference indicate corresponding parts in all the figures.

My invention has relation to that class of nut-locks which are more particularly intended for use on rail-joints, in which the nut is prevented from working or rattling loose upon the bolt after it has been screwed home by means of a coiled spring fastened upon the washer-plate and overlapping one of the sides or faces of the nut, so as to hold the same in place and prevent its turning in the direction which would loosen it, while it does not prevent the nut from being turned home upon the bolt; and my invention consists in certain new and useful improvements upon the nut-lock 35 for which Letters Patent of the United States No. 363,594 were granted to me bearing date of May 24, 1887, and will be hereinafter fully described and claimed.

40 Referring to the several parts by letter, A and B indicate the fish-plates on each side of the end of a rail at a rail-joint.

45 C indicates the bolt, and D indicates the nut, which latter may be square, hexagonal, or octagonal, as desired. The bolt and nut are of 50 the usual construction, requiring no change whatever to adapt them to be used for my im-

proved locking device. This latter consists of the washer-plate E, which bears with its flat inner side against the fish-plate and with its under edge against the flange of the fish-plate or the foot of the rail, as the case may be, to prevent its turning on the bolt.

The washer-plate E is formed with the central outwardly-projecting collar, F, which encircles the bolt-hole and the bolt and forms a bearing around which the spring is twisted, as hereinafter described, this sleeve projecting out and forming a bearing or abutment for the nut, which prevents the latter from being screwed up against the spring, so as to destroy or weaken the tension or elasticity of the same, so that a positive lock will always be formed by the overlapping part of the spring. This collar also forms a firm bearing or seat for the spring, whether the device is in use or not.

In Figs. 1, 2, and 5 of the drawings I have shown the washer-plate E formed with only two projections or retaining lugs or ears, G and H. These ears are preferably formed by striking them out of a sheet of malleable iron integral with the washer-plate with a suitable die, and bending them up and over as required, as shown in the complete device in the said figures, the said ears being shown in Fig. 3 as they appear before being bent up into their operative positions.

I indicates the locking-spring used with this form of washer-plate, consisting of a coiled spring adapted to fit in the washer-plate closely around the central collar, F, with one of its ends and its main body portion, but with its free end portion bulging or bent up or outwardly slantingly, as shown, so as to overlap the nut when the latter is screwed home on the bolt. This spring I is secured on the washer-plate by the ears G and H being bent over its inner portion and end, as shown in Figs. 1 and 2 of the drawings, and encircling the central collar, F, while its free end portion rises slantingly, as shown, the bulging or projecting portion of the spring slanting inwardly to the left, so that in operation the nut may be screwed home, its corners passing over the incline of the outwardly-curved end of the locking-spring and forcing the said end in so as to ride over it until the nut is screwed tight home against the

outer end of the central collar, F, which forms a firm bearing or abutment for it, and prevents it from being screwed against the spring so as to destroy or weaken the tension or elasticity 5 of the same, and also to permit the spring to form a positive lock, as when the ends of the nut pass over the raised portion of the spring the tension of the spring will throw out its free bent end, so that the said end portion will abut 10 against the flat side or face of the nut and prevent the same from being turned backward to unscrew it from the bolt unless the spring is forcibly depressed by hand for that especial purpose, the spring thus forming a strong, reliable, and positive lock which will effectually 15 prevent the nut from rattling or working loose on the bolt, as it is impossible for it to turn backward to loosen itself on the bolt.

The form of nut-lock above described is especially adapted for locking small nuts upon 20 the bolts, either small square nuts or octagonal nuts.

In Fig. 3 of the drawings I have shown the washer-plate formed with five projections or 25 retaining lugs or ears, J, K, L, M, and N, the four lower ears, J, K, L, and M, being adapted to be bent over the inner portion and end of the spring O, and thus retain the said spring in position on the washer-plate, while the 30 other and upper ear, N, is not bent, but remains straight, and serves to protect the spring at its free portion and prevent it from being forced out of place in turning the nut. O indicates the locking-spring used with this form 35 of washer-plate, consisting of a coiled spring adapted to fit in the washer-plate closely around the central collar, F, thereof, with one of its ends and its main portion secured by the bent-over ears J, K, L, and M, while its free 40 end portion is bent up and outwardly slantingly, as shown, so as to overlap the nut when the latter is screwed home on the bolt, while the raised outer end of the spring projects out beyond the corner of the nut. This form of my 45 nut-lock above described, and shown in Fig. 3, is especially adapted for locking square nuts up upon the bolts, and will lock a one-and-one-fourth-inch or a one-and-one-half-inch nut equally well, as the bulge or bend O' is formed in this spring near the free end of the same at a greater distance from the bolt than in the other forms of spring shown, by which arrangement the spring is adapted for 50 rather larger square nuts especially. The 55 number of lugs or ears on the washer-plate may be reduced, five being employed in order to render the plate effective if one or more of the said ears should break or crack in bending.

In Fig. 4 of the drawings I have shown the 60 washer-plate formed with three lugs or ears, P, Q, and R, the ears P and Q being adapted to be bent over the spring S to hold it in place

on the washer-plate E' around the central collar, F, thereof, while the third lug or ear, R, is not bent, but serves to protect the spring at 65 its free portion and prevent it from being forced out of place in turning the nut. S indicates the coiled spring which is used with this washer-plate, having the bulge or bend S' formed in it nearer the bolt than in the spring 70 O, this form of spring being adapted for locking hexagonal and smaller square nuts on the bolt, as the outward slant or bulge S' is formed in the spring at a point closer to (nearer) the bolt than in the spring shown in Fig. 3. The 75 straight lug R may be dispensed with, as may also the straight lug N of the washer-plate E', if its use is found to be not required. The collars F of the several washer-plates are precisely similar to each other, and have the same 80 functions.

From the foregoing description, taken in connection with the accompanying drawings, the construction, operation, and advantages of my invention will be readily understood. 85 It will be seen that my improved nut-lock is simple and strong in construction, can be applied to any rail-joint without any change of the fish-plates, bolt, or nut, and is exceedingly effective in its operation, as it will effectually 90 prevent the nut from working off of the bolt.

The several forms of locks are substantially similar in construction, varying only in small points to adapt them for nuts of different sizes and different number of sides. The projecting sleeve or collar F of each washer-plate forms a bearing for the nut, and prevents it from being screwed up against the spring so as to destroy the elasticity or tension of the same, so that a positive lock will always be 100 formed by the spring.

Having thus described my invention, what I claim, and desire to secure by Letters Patent of the United States, is—

In a nut-lock, the combination, with the 105 locking-plate formed with a central outwardly-projecting collar, the retaining ears or lugs arranged around said collar upon said plate, and also a protecting-lug, and a coiled locking-spring adapted to be secured between the 110 collar and the ears or lugs, having its free end bulged outwardly and slantingly, and adapted to overlap the nut when screwed home and to be retained in place by the protecting-lug, substantially as and for the purpose shown 115 and set forth.

In testimony that I claim the foregoing as my own I have hereunto affixed my signature in presence of two witnesses.

GREVILLE E. CLARKE.
